UNITED STATES PATENT OFFICE

161,569

JAR CAP OPENER

Elva E. Bushman, Chicago, Ill.

Application August 8, 1949, Serial No. 4,360

Term of patent 14 years

(Cl. D44—29)

To all whom it may concern:

Be it known that I, Elva E. Bushman, a citizen of the United States, residing at Chicago, in the county of Cook and State of Illinois, have invented a new, original, and ornamental Design for a Jar Cap Opener, of which the following is a specification, reference being had to the accompanying drawing.

In the drawing:

Fig. 1 is a top plan view of a jar cap opener, embodying my design;

Fig. 2 is a sectional view taken approximately on the line 2—2 of Fig. 1; and

Fig. 3 is a fragmentary sectional view taken approximately on the line 3—3 of Fig. 2.

I claim:

The ornamental design for a jar cap opener, as shown.

ELVA E. BUSHMAN.
